DESIGN FOR A COMBINATION TOKEN AND ASH HOLDER

Frank L. Weiss, New York, N. Y.

Application January 11, 1941, Serial No. 97,973

Term of patent 7 years

To all whom it may concern:

Be it known that I, Frank L. Weiss, a citizen of the United States, residing in county of Bronx, city and State of New York, have invented a new, original, and ornamental Design for a Combination Token and Ash Holder, of which the following is a specification, reference being had to the accompanying drawing, forming part hereof.

Fig. 1 of the drawing is a top plan view of a combination token and ash holder embodying my design.

Fig. 2 is a side elevational view thereof.

Fig. 3 is a bottom plan view thereof.

Fig. 4 is a side view of the device looking from the left of Fig. 2, on a somewhat smaller scale.

The side of the device opposite to that shown in Fig. 2 is substantially similar to the side therein shown.

I claim:

The ornamental design for a combination token and ash holder, as shown and described.

FRANK L. WEISS.
